Primary Examiner — Sheryl Lane*Assistant Examiner* — Ieisha Price(74) *Attorney, Agent, or Firm* — Kilpatrick Townsend & Stockton LLP(57) **CLAIM**

The ornamental design for a wall fastener, as shown and described.

DESCRIPTION

FIG. 1 is a perspective view of the top and one side of the fastener of this invention.

FIG. 2 is a first side view of the fastener shown in FIG. 1.

FIG. 3 is a second side view of the fastener shown in FIG. 1 with the fastener rotated 90 degrees about its longitudinal axis as compared to FIG. 2.

FIG. 4 is a third side view of the fastener shown in FIG. 1 with the fastener rotated 90 degrees about its longitudinal axis as compared to FIG. 3.

FIG. 5 is a fourth side view of the fastener shown in FIG. 1 with the fastener rotated 90 degrees about its longitudinal axis as compared to FIG. 4.

FIG. 6 is a top plan view of the fastener shown in FIG. 1; and, FIG. 7 is a bottom plan view of the fastener shown in FIG. 1. The broken lines in the drawings illustrate portions of the wall fastener and form no part of the claimed design.
